UNITED STATES PATENT OFFICE

2,105,411

SPARK PLUG

Kenneth C. De Walt, Schenectady, N. Y., assignor to General Electric Company, a corporation of New York

Application August 1, 1936, Serial No. 93,855

4 Claims. (Cl. 123—169)

The present invention comprises an improved spark plug for internal combustion engines.

Heretofore it has been common practice to insulate from one another the oppositely charged parts of a spark plug by an elongated insulator commonly consisting of porcelain. The central conductor is threaded through the insulator which is mechanically clamped by a screw-threaded member within the casing of the plug. It is well known that some disadvantages accompany such a construction. For example, the end of the insulator is subject to carbon deposition from the combustion mixture and the insulator sometimes is cracked by the compressive forces to which it is subjected, when it consists of opaque material, such as porcelain, the light from the spark cannot be seen from the exterior and hence the operativeness of the spark plug cannot be ascertained by observing light emitted by the plug.

In accordance with the present invention all such difficulties are absent and a convenient structure is provided by making part of the shell or outer member of a spark plug of glass which is integrally united or welded to adjoining metal parts. No other insulator need be provided between the sparking conductors. An internal conductor is joined to a metal portion of the shell at the end of the plug which is remote from the location of the terminals between which the spark occurs. If partial obscuration of the light emitted by the spark can be tolerated, a baffle is provided between the sparking terminals and the glass insulator, thereby preventing deposition of carbon or other conductive material upon the inner surface of the insulator.

The accompanying drawing shows in Fig. 1 a longitudinal section of a preferred form of spark plug embodying my invention; Figs. 2 and 3 are longitudinal sections of modifications; and Fig. 4 is a perspective enlarged view of a baffle and support employed in the modification of Fig. 3.

Referring to Fig. 1, the spark plug illustrated consists of an elongated shell or housing made up of a heavy-walled metal body portion 1, a glass portion 2, and a relatively thin-walled metal cap portion 3. An interior conductor 4 is attached at one end to the cap portion 3 of the shell. It terminates at the opposite in a sparking tip 5, which as illustrated, may have a smaller cross section than the main portion of the conductor 4. The sparking tip 5 cooperates with a similar sparking tip 6 projecting from the screw-threaded portion 7 of the plug which is constructed to engage with an opening in the wall of

an engine cylinder. The attached end of the conductor 4 is grooved at 8 and is firmly gripped by the cap 3, which engages with the groove.

The body portion 1 terminates at the end opposite the spark tip 6 in a lip 9 of reduced thickness which preferably tapers down to an even smaller rim. The opposite rims of the glass cylinder 2 are sealed by fusion to the rim of the lip 9 and the rim of the cap 3. The seals between the glass and the metal members are maintained strain-free by so choosing the glass and metal that the thermal expansion characteristics of the glass and metal are substantially coincident at temperatures below the zone of transformation temperatures of the glass, that is, at the zone of temperature at which the thermal expansion characteristics rapidly increase with temperature. Such a seal is described in a copending application, Serial No. 705,250, filed January 4, 1934 by E. E. Burger and A. W. Hull (see corresponding French Patent 784,164 issued April 23, 1935). This seal also is described in an article by A. W. Hull and E. E. Burger in Physics, Vol. 5, No. 12, pages 384-411. As there explained, a suitable strain-free seal may be made by sealing a hard glass, sold in the open market by the Corning Glass Co. of Corning under the name "Corning G-71", to metal members having suitable thermal expansion characteristics, for example, an alloy consisting of 54 per cent iron, 28 per cent nickel and 18 per cent cobalt. The above application and article describes various equivalents for this particular glass and this particular metal alloy.

If desired, the member 1 may be constructed of two parts brazed or otherwise joined to another, the thick walled part 1a consisting of iron or other inexpensive metal and the lip 9 consisting of alloy suitable for joining to glass.

In the spark plug shown in Fig. 1, the space between the inner conductor 4 and the outer shell is unobscured so that light from the spark between the tips 5 and 6 may be seen through the glass member 2. The condition of the spark thus may be observed and the condition of the plug thus may be determined, without the necessity of using special testing appliances or removing the plug.

In the modification shown in Fig. 2, the metal baffle 11 is mounted upon the inner conductor 4, the walls of the shell 1 being somewhat cut away as indicated at 12. Particles of metal, carbon, or other conducting material can only reach the inner surface of the glass window 2 through a sinuous elongated path. Hence the amount of such deposition will be greatly decreased. The

baffle 11, as indicated, consists of a cylindrical portion and an outwardly extending radial portion, the former making frictional engagement with the conductor 4.

5 In the modification shown in Fig. 3, the baffle 14 consists of an insulating material such as alumina, magnesia, porcelain or silica. It is shown somewhat enlarged in Fig. 4 together with the holder 15 whereby it is mounted upon the 10 conductor 4. The support 15 makes a frictional engagement, both with baffle 14 and the conductor 4. The segmental members 15a may be bent outwardly to engage firmly and positively with the baffle 14.

15 What I claim as new and desire to secure by Letters Patent of the United States is:

1. A spark plug for internal combustion apparatus comprising the combination of a hollow casing the wall of which consists of metal and 20 glass having approximately the same thermal coefficient of expansion, said metal and glass members being fusion-sealed to one another at adjacent edges and a cooperating conductor located within said casing and being connected at one 25 end only with said casing.

2. A spark plug for internal combustion apparatus comprising the combination of a hollow

casing consisting of a plurality of metal members and an intermediate hollow cylindrical glass member which is sealed at opposite ends to said respective metal members and a cooperating conductor sealed to one of said members and extending in sparking relation to another of said metal members. 5

3. A spark plug for internal combustion apparatus comprising the combination of a hollow casing consisting of a metal base, a cap and a 10 glass insulator which is fusion-sealed to said base and cap, a conductor sealed to said cap and projecting through said casing and a baffle mounted on said conductor.

4. A spark plug comprising the combination of 15 a massive, hollow metal base constructed to engage with an engine cylinder wall, said base having a rim of reduced thickness, a hollow glass cylinder sealed at one rim thereof to said base rim, a cap closing the opposite rim of said glass 20 cylinder and being fusion-sealed thereto, a conductor extending from said base, and a second conductor joined to said cap, projecting longitudinally through said casing and extending in sparking relation to said base conductor. 25
